UNITED STATES PATENT OFFICE.

WALTER L. MARR, OF FLINT, MICHIGAN.

CARBURETER.

1,194,530.

Specification of Letters Patent. Patented Aug. 15, 1916.

Application filed March 17, 1915. Serial No. 15,101

To all whom it may concern:

Be it known that I, WALTER L. MARR, a citizen of the United States of America, residing at Flint, in the county of Genesee and State of Michigan, have invented certain new and useful Improvements in Carbureters, of which the following is a specification, reference being had therein to the accompanying drawings.

10 This invention relates to carbureters and to an arrangement thereof whereby the successful operation thereof is not dependent upon the piston speed of the motor to which the carbureter may be attached, the parts being so disposed that the motor is supplied with a sufficiently rich mixture, even under slow speed, to insure regular firing and consequent proper running of the engine.

15 The invention consists of the matters hereinafter set forth, and more particularly pointed out in the appended claims.

20 In the drawings, Figure 1 is a view in vertical longitudinal section taken through a carbureter that embodies features of the invention, showing the main valve in open position; Fig. 2 is a view in transverse section taken on or about line II-II of Fig. 1; Fig. 3 is a view in vertical longitudinal section taken at substantially right angles to the 25 plane of view of Fig. 1 showing the main valve closed, and an auxiliary fuel feed valve.

25 Referring to the drawings, a carbureter body which may be of any preferred appropriate design and which is herein shown as consisting of a base section 1, intermediate section 2 and head section 3, is provided at the lower or base section with a fuel chamber to which the supply of fuel may be regulated, if desired or preferred, by any well known means, as for example a float 4 controlling a suitable feed valve (not shown). A diaphragm 5 forms a dividing wall between the lower base section and the intermediate section 2, such diaphragm as herein shown being formed integrally with a depending stem 6 that for purposes of simple mechanical construction may form means for attaching the base thereto by screw-threaded engagement. A main annular valve seat indicated at 25 is formed in a diaphragm 7, intermediate a lateral air inlet 8 in the middle section and an air outlet in the upper section 3, the outlet being controlled by a throttle valve 9 of appropriate type.

30 A lift closure disk 10 seals the opening encircled by the valve seat 25, a depending valve stem 11 being reciprocal in a guide opening of the stem 6. A bushing 12 with 60 slightly downwardly tapered bore is mounted in axial alinement, preferably, with the valve seat 25 in a bridge 13 across the interior of the carbureter, herein illustrated as formed in the upper section 3. A main pipe 65 14 extends from the fuel chamber of the base 1 into a duct 15 that is regulatably controlled by a suitable valve, as for example the needle closure 16 so that the outlet thereof may discharge to a greater or less extent 70 into a peripheral groove 26 formed in the outer surface of the bushing 12, apertures 17 forming communicating openings between the groove and the bore of the bushing. A plug closure 19 adapted to seal the 75 bushing 12 is adjustably mounted on the closure 10 as by means of a depending stem rod 20 longitudinally adjustable in a suitable opening of the closure 10 and its depending stem 11.

80 The adjustment between the closure 10 and the plug 19 is such that when the motor to which the carbureter is attached is running at or between predetermined speeds, the closure 10 unseats the plug 19 and thereby permits the aspirator effect of the inrushing column of air due to the suction of the motor to volatilize the injected or indrawn fuel and project it through the outlet of the carbureter.

85 An auxiliary speed tube 21 leads from the fuel chamber in the base 1 of the carbureter to an auxiliary inlet duct 22 having an upwardly extending jet pipe forming its outlet, that discharges into a vaporizing tube 95 23 extending through the diaphragm 7. The flow through the passage 22 is controlled by regulating valve which may take the form of a needle closure 24.

90 When set for action the auxiliary feed 100 pipe or tube is opened sufficiently so that when at low speed and before the suction is sufficient to lift the closure disk 10, the inrushing air passes through the comparatively small aspirating tube into which the auxiliary jet tube discharges, the fuel is vaporized and carried along by the current of air, which moves rapidly through the comparatively small opening, to fully supply the motor even at low speed so that there is 105 no danger of missing or of failing to operate. When the motor attains high speed 110

or any speed within the limit for which the carbureter is set for regular use, the main closure lifts and thereby opens the main supply valve, the air passing through the 5 comparatively wide annulus around the main valve closure and past the main feed valve outlet with sufficient speed to thoroughly volatilize the incoming fuel and thereby give the motor a normal supply.

10 While the details of construction may be varied to meet the different requirements of service, the general design of the carbureter herein shown is preferred as it simplifies the machining and assembling of the parts, 15 while at the same time the air passages are so proportioned and divided that the requisite velocity is maintained even at slow speed of the engine, to obtain the desired aspirating effect at the auxiliary valve nozzle so that the resultant mixture is fired regularly 20 in all of the motor cylinders. At high speed the disk closure lifts and so increases the area of the air passage through the carbureter that the velocity of the air past the 25 auxiliary valve nozzle falls so that the auxiliary valve is not effective to cause an injector effect at this point, while the main valve is drawn on for the supply. Thus, since the main valve is raised to a greater 30 or less extent in accordance with the force of the motor air intake, the supply from the main valve automatically adjusts itself to the motor speed within the range for which the carbureter is designed to operate after 35 the low speed auxiliary air valve becomes idle.

Obviously, changes in the details of construction may be made without departing from the spirit of my invention and I do not 40 care to limit myself to any particular form or arrangement of parts.

What I claim is:—

1. In a carbureter, a casing having an air inlet and outlet, a diaphragm across the carbureter between the inlet and outlet provided with a restricted auxiliary air opening that is constantly open and a main air opening, a closure for sealing the main opening through the diaphragm when the air 45 velocity through the carbureter falls below a predetermined point, fuel supply means discharging into the casing between the diaphragm and the outlet, operated by the main opening closure, and means for delivering 50 fuel into the constantly open auxiliary air passage.

2. In a carbureter, a casing having an air inlet and an air outlet, a diaphragm between the inlet and outlet having a constantly open 60 restricted auxiliary air passage and a comparatively large main air opening, a closure for the main opening normally seated by gravity, fuel vaporizing means controlled by the closure to open when the latter uncovers 65 the main opening and adapted to discharge

into the casing between the diaphragm and the outlet thereof, and means for delivering fuel into the auxiliary air passage.

3. In a carbureter, a fuel chamber, a diaphragm between an air inlet in the carbureter and an air outlet therefrom, provided with a restricted air passage that is always open and a main air passage, a closure for the main passage, a fuel supply valve opened by the movements of the 70 closure for delivering fuel from the fuel compartment between the diaphragm and air outlet, and an auxiliary fuel valve adapted to deliver fuel from the fuel compartment into the auxiliary air passage. 80

4. In a carbureter, a casing having a fuel compartment, and an air inlet and outlet connected by a main air passage, a diaphragm across the passage between the inlet and outlet having a restricted auxiliary 85 air opening and a main air opening, a closure sealing the main air opening and lifting therefrom under influence of air passing from the inlet to the outlet, a fuel regulating valve controlling a main duct 90 from the fuel compartment that opens into the main air passage between the diaphragm and air outlet, an auxiliary fuel valve controlling a duct leading from the fuel compartment and discharging into the constantly open auxiliary air opening, and a closure for the main duct outlet that is 95 operated by and in unison with the main air opening closure.

5. A carbureter comprising a base having 100 a fuel supply compartment, an intermediate section mounted on the base and provided with an air inlet and a diaphragm having a main air opening and a restricted auxiliary air opening, a fuel duct leading from the fuel compartment and discharging into the 105 restricted auxiliary opening, a valve regulating the flow through the duct, a cap mounted on the intermediate section having an air outlet, a main fuel supply duct leading from the fuel compartment and discharging into the cap above the main diaphragm opening of the intermediate section, a closure restricting and sealing the discharge of the main fuel duct, and a 110 closure for the main diaphragm opening adapted to be lifted therefrom by air passing from the inlet to the main outlet and arranged to operate the main fuel duct closure in response to the closure movement. 115

6. In a carbureter, a casing having an air inlet and an air outlet, a diaphragm in the casing across the passage between the air inlet and outlet having a restricted 120 constantly open auxiliary air passage and a main air opening, a fuel duct discharging into the auxiliary air passage, a regulating valve for the fuel duct, a closure for the main opening adapted to be moved there- 125 130

- from by air passing from the inlet to the outlet, a main fuel duct discharging into the casing between the diaphragm and the main air outlet, a closure regulating the discharge from said main duct, and moving in unison with the diaphragm opening closure to which it is connected, and a throttle valve controlling the main air outlet of the carbureter.
- 10 7. In a carbureter, an intermediate section having a stem depending from the base thereof, a base section including a fuel compartment secured to the intermediate section by the stem, a diaphragm across the intermediate section having a restricted air passage and a main air opening, a closure for the main opening having a stem in sliding engagement with a guide opening in the depending stem, a fuel supply duct leading from the fuel compartment of the base and discharging into the restricted air passage, a regulating valve for the duct, a cap on the intermediate section having an air outlet in communication through the restricted air passage and the main air opening, with an air inlet in the intermediate section, a main fuel duct leading from the fuel compartment and discharging through diffusing openings into the interior of the cap, and a closure for the diffusing openings connected to the main air opening closure and operated thereby.
- 15 8. In a carbureter, a base having a fuel compartment; an intermediate section on the base having a central depending stem 31 by which the base is secured, a diaphragm closing the upper end of the intermediate section and having a restricted always open auxiliary air passage, and a main opening both in communication with an air inlet to 40 the intermediate section, an auxiliary fuel duct from the fuel compartment having a jet nozzle discharging into the restricted air passage, means for regulating the flow through the duct, a closure adapted to seal 45 the main opening and provided with a guide stem longitudinally reciprocable in the depending section stem, a cap mounted on the intermediate section, a taper bored bushing in the cap in the air passage thereof connecting an outlet from the cap with the openings of the diaphragm, a main fuel duct leading from the fuel compartment and passing through lateral openings in the inner periphery of the bushing, and a closure 50 55 adapted to seal the bushing and connected to the main opening closure to move in unison therewith.
- In testimony whereof I affix my signature in presence of two witnesses.
